UNITED STATES PATENT OFFICE

LEO F. HENEERRY, OF ROANOKE, VIRGINIA, ASSIGNOR TO NORFOLK & WESTERN VETERANS ASSOCIATION, OF ROANOKE, VIRGINIA

DESIGN FOR A LAPEL BUTTON

Application filed February 21, 1930. Serial No. 34,601. Term of patent 14 years.

To all whom it may concern:

Be it known that I, LEO F. HENEERRY, a citizen of the United States, residing at Roanoke, in the county of Roanoke and State of Virginia, have invented a new, original, and ornamental Design for a Lapel Button, of which the following is a specification, reference being had to the accompanying drawing, forming part thereof.

Figure 1 shows a plan view of the new design for a lapel button.

Figure 2 shows a side elevation of the same.

I claim:

The ornamental design for a lapel button, as shown.

LEO F. HENEERRY.
